UNITED STATES PATENT OFFICE.

WESLEY WAIT, OF NEWBURGH, NEW YORK.

METALLIC BONDING FOR CONCRETE SUPPORTS.

Application filed February 9, 1927. Serial No. 167,006.

This invention relates to improvements in metallic bonding structure for reinforcing concrete supports, such as foundations for heavy buildings and mine pillars subjected to excessive crushing strains from overhead loads and also bulkheads employed in mine caisson and subway construction to withstand heavy lateral pressure. It is customary to construct such supports of concrete reinforced by a metallic skeleton or retaining casing, the concrete providing the bulk and the skeleton or casing imparting the required stability. The object of the instant invention is to provide a metallic casing for such supports, formed of heavy units having an interlock that facilitates ready assembly of the parts in a composite whole, the casing so formed providing an efficient reinforcement and container for the concrete. The invention is described in detail hereinafter, illustrated by the accompanying drawings and defined in the appended claims.

In the drawings, in which similar characters designate corresponding parts:

25 Figure 1 is a side elevation of a cubical support of reinforced concrete embodying the invention, said support may be a mine pillar or a foundation for a structural column.

30 Figure 2 is a vertical sectional view on the line 2—2 of Fig. 1.

Fig. 3 is a horizontal sectional view on the line 3—3 of Fig. 2.

Figure 4 is a vertical sectional view on the line 4—4 of Fig. 3.

Figure 5 is a vertical sectional view on the line 5—5 of Fig. 4.

Figure 6 is a detail view, showing a cross-section of one of the structural units with its upper channel filled with concrete preliminary to placing thereon the covering unit.

40 Figures 7 to 10, inclusive, are detail perspective views of the several structural units employed in the construction of the reinforcement.

Figure 11 is a detail view showing the joint of two units in oblique relation.

Figures 12 and 13 are diagrammatic views, respectively showing an elevation and a plan 50 of bulkhead embodying the invention.

Referring to the drawings in detail, 15, 16, 17 and 18 designate several structural units employed in the construction of a mine pillar or column support. The units 16 and 17 are 55 alike in formation, but the two are shown with different reference characters to design-

nate similar parts; the purpose of this is to facilitate the description of the assembled parts. The several units are made of channel iron, mainly of H-shape section, and have 60 their flanges notched and recessed at the ends to provide a mutual interlock. The unit 15 shown in part in Fig. 7 is a base member, comprising an iron with a single channel and a flat base. In each end of this 65 member, in the flanges thereof, are the notches 14 extending to the web 19 of the iron. The outer edges of the flanges are cut away to a slight depth between the notches 18, as at 20.

70 The unit 16, shown in Fig. 8, is an iron channeled on opposite sides to form an H-shape section and in the flanges at each end and on one side are the notches 22 cut through the flanges to the web 23. The 75 flanges between the notches at each end of the iron are slightly cut away as at 24. The flanges on the other side of the iron are recessed at their ends, as at 25, opposite to the notches 22. The unit 17, as shown in Fig. 80 9, is also an iron channeled on opposite sides to form an H-shape section, the flanges on one side of which are provided at their ends with notches 26 that extend to the web 27, and between each pair of notches the flange 85 is cut away, as at 28. The flanges on the other side of the iron are slightly recessed, as at 29, opposite to the notches 26. The unit 18, one end of which is shown in Fig. 10, is an iron channeled on but one side and in 90 the ends of its flanges are the shallow recesses 30.

95 In the construction of a foundation pier or mine pillar, as illustrated in Fig. 1—5, on a prepared level surface are placed two of the units 15, which may be termed base units, in parallel relation with their flanged sides upward. Then across the opposite ends of these base units are placed a pair of the intermediate units 16. In the mutual 100 arrangement of the base and intermediate units, the flanges of the units 16 having the recesses 25 are seated in the notches 14 of the members 15 with the bodies of the base members registering with the said recesses. 105 Then a pair of the other intermediate units 17 are crossed over the ends of the previously positioned members 16, the ends with the recesses 29 being seated in the notches 22 of the member 16 with the flanged 110 parts between the notches 22 entering the under channel of the unit 17 between the

flanges of the latter having the recesses 29. In this relative position of the two members 16 and 17, the recessed flange parts 24 of the member 17 are seated in the notches 22, 5 the shoulders at the ends of the recesses 24 extend downward outside of the member 16. In this way, successive pairs of the intermediate units are alternately positioned until the desired height of the structure is 10 obtained. On the top pair of intermediate units, as the uppermost units 17 in Figs. 1 and 2, is placed a pair of crowning units 18. Each of these units comprises an iron with a single channel and the ends of the flanges 15 are slightly recessed, as at 30. These crowning irons are placed cross-wise of the ends of the units 17 with their flanges at the recesses 30 registering with the notches 22. When so placed the crowning irons 18 top 20 the notched ends of the units 17 and also the entire length of the pair of units 16 immediately below.

By arranging and combining the units in the foregoing manner, a rectangular structure is formed with walls having a thickness equal to the widths of the channel irons. 25 These parts are securely interlocked to withstand lateral strain and the superimposed members are capable of withstanding 30 the crushing force of heavy weight. To add to the stability of the structure, the interior space is filled with concrete 31, and the spaces between the channel irons which are of a cell-like formation, are also filled with 35 concrete 32. In placing the concrete 32, the upper channel of a unit is heaped full of the concrete, as shown in Fig. 6. The unit to be positioned above is then forced downward on the heaped concrete, which fills the under 40 channel of the upper member and the surplus material is forced outwardly as the flanges come together.

For some purposes it may be desirable to give to the support a shape other than rectangular, hexagonal or octagonal for instance. To provide such shapes, the notches and recesses in the flanges of the engaged members are cut diagonally across the same, as indicated in Fig. 11.

50 In the construction of bulkheads, where the walls of the casings have considerable length, the length of the channel irons in one direction may be elongated to extend across several of the spaced channel irons extending 55 in the other direction, as shown in Figs. 12 and 13. Here, the abutting ends 33 of the extended units are positioned with relation to a cross member, so that one of the flanges of the cross member engages one of 60 the abutting ends and the other flange engages the other abutting end so as to provide a rigid connection between the abutting ends, as shown in Figs. 12 and 13.

What I claim is:

65 1. A metallic bonding structure including

walls in angularly disposed relation, each wall comprising a series of superimposed channel irons arranged with their flanges in abutting relation and with the channel irons of one wall breaking joint with the channel 70 irons of the other wall, and an interlock connection between the channel irons of both walls that mutually break-joint.

2. A metallic bonding structure including 75 walls in angularly disposed relation, each wall comprising a series of superimposed channel irons arranged with their flanges in vertical abutting relation, the channel irons of one wall breaking joint with the channel irons of the other wall, the channel irons of 80 one wall being interposed at their ends between the ends of the channel irons in the other wall, and an interlock connection between the interposed ends of the irons.

3. A metallic bonding structure including 85 walls in angularly disposed relation, each wall comprising a series of superimposed channel irons arranged with their flanges in vertical abutting relation, the channel irons of one wall breaking joint with the channel 90 irons of the other wall, the channel irons of one wall being interposed at their ends between the ends of the channel irons in the other wall, and the interposed ends having 95 their flanges notched and recessed to provide a mutual engagement between the said ends.

4. A metallic bonding structure including 100 walls joined together in angular relation, each wall comprising a series of superimposed H-sections with their webs horizontally disposed in the wall and the flanges of adjacent sections abutting at their edges to close both sides of the wall; the ends of the sections of one wall being interposed transversely of and in alternate arrangement 105 with the ends of the sections of an adjoining wall; and the flanges of the interposed ends of the sections being mutually interlocked to join the walls in closed relation, to maintain the sections of each wall in their superimposed positions and to hold the individual sections against longitudinal displacement. 110

5. A metallic bonding structure including 115 walls joined together in angular relation, each wall comprising a series of superimposed H-sections with their webs horizontally disposed in the wall and the flanges of adjacent sections abutting at their edges to close both sides of the wall; the ends of the sections of one wall being interposed transversely of and in alternate arrangement with the ends of the sections of an adjoining wall; and the flanges of the interposed ends of the sections being notched and cut away to provide a mutual interlock between the transverse ends to join the walls in closed relation, to permit contact of the edges of the flanges of the sections in each wall, to maintain the sections of each wall in their superimposed relation and to hold the individual 120 sections against longitudinal displacement. 125

13

sections against longitudinal displacement.

6. A metallic bonding structure including walls joined together in angular relation, each wall comprising a series of superimposed H-sections with their webs horizontally disposed in the wall and the flanges of adjacent sections abutting at their edges to close both sides of the wall; the ends of the sections of one wall being interposed 5 transversely of and in alternate arrangement with the ends of the sections of an adjoining wall; and the interposed end of each section having notches formed in the flanges on one side of the end to receive the flanges of the adjacent transverse section, the edges of the flanges between the notches being slightly cut away to admit the web of 10 the transverse section and the engaging edges of the flanges of the transverse section 15 being slightly cut away to admit the web 20

of the end with the notched flanges, to form an interlocking joint between the ends of the adjacent sections, said joint permitting contact between the edges of the flanges of adjacent sections in each wall to close both 25 sides of the wall.

7. In a metallic bonding structure, the combination of lower and upper H-sections in mutual transverse relation, the lower section having its upper flanges notched to receive the lower flanges of the upper section, said flanges of the lower section having their edges slightly cut away between the notches 30 therein to admit the web of the upper section and the upper section having the engaged part of its lower flanges slightly cut away to straddle the lower section. 35

In testimony whereof I affix my signature.

WESLEY WAIT.
